UNITED STATES PATENT OFFICE

JOSEPH AUGUSTIN BOMBARD AND ROLAND JAMES ROGERS, OF SARANAC LAKE, NEW YORK, ASSIGNORS OF ONE-HALF TO ELIZABETH WHITE DIXON, OF BALTIMORE, MARYLAND

VENTILATOR

Application filed January 14, 1929. Serial No. 332,403.

The present invention is directed to improvements in ventilators.

The primary object of the invention is to provide a device of this character more particularly designed for use in connection with railway coaches, but is not necessarily limited to such use.

Another object of the invention is to provide a device of this character so constructed that fresh air can be admitted to the interior of the coach or other closed vehicle, provision being made to prevent cinders, dust, or other particles entering the interior of the coach with the incoming air.

Another object of the invention is to provide a device of this character constructed in such manner that the supply of fresh air can be conveniently regulated.

Another object of the invention is to provide a device of this kind which is simple in construction, durable, efficient in operation, and one which can be manufactured at a small cost.

With these and other objects in view, this invention resides in the novel features of construction, formation, combination and arrangement of parts to be hereinafter more fully described, claimed and illustrated in the accompanying drawing, in which:

Figure 1 is a side elevation of a railway coach showing the ventilators in place thereon.

Figure 2 is a fragmentary side view of the coach showing a ventilator in place upon the dome thereof.

Figure 3 is a plan view of an automobile, partly in section showing the adaptation of the invention thereto.

Figure 4 is a sectional view on line 4—4 of Figure 1.

Figure 5 is a sectional view on line 5—5 of Figure 4.

The ventilator comprises a casing 1 preferably formed from sheet metal, said casing having a restricted central portion 2 into one side of which opens a collar 3, said collar being engaged in an opening 4 formed in the lower rail 5 of the coach window 6. The collar is spaced from the wall of the opening 4 to accommodate the rim 7 of the cap 8, said

rim having openings 9 formed therein and which are closed by screens 10. The top 11 of the cap 8 is provided with a handle 12 to facilitate adjustment of the cap.

Extending into the collar 3 are baffle plates 13—13 which have curved sections 14—14 suitably secured to the outer wall of the casing 1. These plates are spaced to accommodate the plate 15 therebetween, the outer end of said plate having stops 16 carried thereby to limit the sliding movement thereof. The plate 15 is provided upon its inner end with a flange 17 adapted to be secured to the top 11 of the cap 8. The plates 13—13 define passages 18—18 in the collar 55 which communicate with the primary air conducting passages 19—19 of the casing 1. The passages 19—19 are closed at their outer ends by screens 20, said passages having mounted intermediate their ends screens 21. 60

As indicated by the arrows in Figure 4, the air, when the coach is in motion, will be forced through the inlet end of one of the passages 19 and communicating passage 18 of the collar, and from thence into the interior of the 75 coach. Obviously a slight suction will be created in the other passages 18 and 19 in order that impure air will be drawn from the coach.

Since the passages 19 are independent the 80 ventilators will efficiently function when the travel of the coach is reversed.

The supply of fresh air can be conveniently regulated upon adjusting the cap 8 upon the collar 3, and the supply can be wholly cut off 85 upon entirely closing the cap.

As shown in Figure 1, the ventilators are applied to the windows of a coach, but they may be placed upon other parts of the coach, as illustrated in Figure 2, wherein a ventilator is shown applied to the dome of the coach. 90

In Figure 3, the ventilator 22 is shown applied to the top of a motor vehicle, the construction thereof being substantially the same as that of the form applied to a coach with 95 the exception of a slight difference in shape, and since the operation is the same a detailed description thereof is not thought necessary.

A ventilator constructed in accordance with the invention may be readily placed upon 10

various types of vehicles and constructed in such manner that fresh air can be directed to the interior of the vehicle without creating a draft.

5 From the foregoing, it is thought that the construction, operation and many advantages of the herein described invention will be apparent to those skilled in the art, without further description, and it will be understood 10 that various changes in the size, shape, and proportion and minor details of construction may be resorted to without departing from the spirit or sacrificing any of the advantages of the invention.

15 What is claimed is:—

1. A ventilator comprising a casing having a collar opening into one side thereof, baffle plates fixed transversely of the casing and extending into the collar to provide independent 20 air passages leading from the end of the casing into the collar, and a cap adjustably mounted upon the collar and having a plate carried thereby for slidable engagement between the baffle plates, as and for the purpose 25 set forth.

2. A ventilator comprising a casing having a collar communicating with the interior of the casing intermediate its ends, baffle plates fixed transversely of the casing and extending 30 into the collar to provide independent air conducting passages, a cap adjustably mounted upon the collar and having screened openings therein to permit egress of air from the passages, and a plate fixed to the cap 35 and slidably associated with the baffle plates.

3. A ventilator comprising a casing having a restricted central portion, a collar opening into one side of said portion, baffle plates fixed transversely of the casing and extending into 40 the collar and dividing the casing and collar into independent air conducting passages, a cap adjustably mounted on the collar and having screened openings communicating with the passages in the collar, and a plate 45 fixed in the cap and slidable between the baffle plates.

4. A ventilator comprising a casing having a collar opening thereinto, baffle plates fixed transversely of the casing and extending into 50 the collar and providing independent air passages in the collar and casing, a cap slidably adjustable on the collar and having screened openings coinciding with the passages, a plate movable with the cap and slidably associated 55 with the baffle plates, screens closing the ends of the casing, and screens mounted in the passages between the end closing screens and baffle plates.

60 5. The combination with the rail of a window having an opening therein, of a casing having a collar opening into the central portion thereof, said collar being adapted to engage in said opening, baffle plates fixed transversely in the casing and extending into 65 the collar, a cap slidably adjustable on the

collar and movable in the opening, and a plate fixed to the cap and slidably between the baffle plates.

6. A ventilator comprising an open-ended casing having a collar opening into one side thereof, baffle plates mounted in the casing and extending into the collar to form independent air passages leading from the open ends of the casing into the collar, a closure cap 70 slidably mounted upon the collar for controlling the egress of air from the passages, and means carried by the cap and cooperating with the baffle plates to prevent withdrawal 75 of the cap from the collar.

In testimony whereof we affix our signatures.

JOSEPH AUGUSTIN BOMBARD. [L. S.]
ROLAND JAMES ROGERS. [L. S.]
